FOOT ACTUATING TROLLING IMPELLER

Walter Reynolds, Conway, Ark.

Application September 11, 1950, Serial No. 184,221

3 Claims. (Cl. 115—25)

1

This invention relates to fishing boats and the like and particularly boats of the row boat or outboard motor type, and in particular a foot actuated rig for mounting on the stern of a small boat with a fish-tail propeller and means actuating the propeller by pedals positioned in the boat.

The purpose of this invention is to eliminate the necessity of using oars or other impelling means in small fishing boats and particularly in boats used for trolling.

In the conventional row boat or outboard motor boat at least one hand of a fisherman is required to control the passage of the boat through the water and numerous fish are lost because it is impossible to drop the control lever when both hands are required to land the fish. With this thought in mind this invention contemplates a foot-actuated propelling and controlling means whereby both hands of a fisherman are free to handle the line.

The object of this invention is, therefore, to provide means for constructing a comparatively small rig that may be mounted on the stern of a row boat or outboard motor boat wherein a fisherman may actuate a fish-tail propeller by foot pedals and may also use the propeller for steering whereby the boat is under control at all times and both hands of the fisherman are free.

Another object of the invention is to provide a foot actuated propeller rig that could readily be installed upon boats now in use without changing the design or construction of the boats.

A further object of the invention is to provide a foot-actuated fish-tail propeller mounting for small boats which is of a comparatively simple and economical construction.

With these and other objects and advantages in view the invention embodies a vertically disposed shaft journaled in a bearing on the bottom of a boat with the upper end held by side braces, an impeller shaft journaled in a bearing suspended from the stern of the boat and also held by side braces, a fish-tail propeller carried on the lower end of the shaft, and cables connecting the shaft in the boat to the propeller shaft.

Other features and advantages of the invention will appear from the following description taken in connection with the drawings wherein:

Figure 1 is a plan view showing the foot actuated fish-tail propeller mounting on the stern of a boat with the forward part of the boat broken away.

Figure 2 is a longitudinal section through the stern of a boat showing the propeller mounting in position thereon.

2

Figure 3 is a cross section through the stern of the boat taken on line 3—3 of Figure 2 showing the foot pedals and cable operating sheave.

Figure 4 is an elevational view showing the stern of the boat.

Figure 5 is a detail showing a section similar to that shown in Figure 2 with the section taken at one side of the mounting showing thumb screws for clamping the propeller shaft bearing to the stern of the boat.

Figure 6 is a detail illustrating a clamp for attaching ends of the braces to the sides of the boat.

Figure 7 is a detail illustrating a propeller blade mounting with other parts omitted.

Figure 8 is a detail showing the lower shaft bearing in the bottom of the boat.

Figure 9 is a detail illustrating one of the thumb screws for attaching the braces to the sides of the boat.

Figure 10 is a plan view illustrating the spider upon which the pedals are carried.

Figure 11 is a detail taken on line 11—11 of Figure 5 showing a flat side of the vertical section of the propeller shaft.

Referring now to the drawings wherein like reference characters denote corresponding parts the fish-tail propeller mounting of this invention includes a vertically disposed stationary shaft 10 having a sleeve with a pedal carrying spider 11 on the lower end and with a pulley 12 on the upper end journaled thereon, a propeller shaft 13 having a horizontally disposed arm 14 with a fork 15 at the outer end thereof, a pulley 16 mounted on the propeller shaft 13 by a sleeve 17, and diagonally disposed braces 18 and 19 for supporting the shaft 10, and 20 and 21, for supporting the shaft 13.

The shaft 10 is mounted in a base 22 having radially disposed arms 23 which are secured to the bottom 24 of a boat by bolts 25 and the sleeve 26 in which the spider 11 and pulley 12 are mounted is journaled on the shaft. The spider 11 is provided with pedals 21, similar to bicycle pedals and the pulley or sheave 12, the diameter of which is greater than that of the pulley 16, is provided with a spiral groove 28 so that a cable 29 is wrapped continuously around the pulley.

The upper parts of the shaft 10 and sleeve 26 are mounted in bearings 30 and 31 on the ends of the braces 18 and 19, respectively and the outer ends of the braces are provided with U-shaped clamps 32 and 33 that fit over the gunwales or upper edges of the sides 34 and 35 of the boat, as shown in Figure 3. The clamp 32

is provided with a thumb screw 36 and the clamp 33 is provided with a similar screw 37.

The brace 18 is provided with an idler pulley 38, which is journaled on a stud 39, and the brace 19 is provided with a similar pulley 40 that is journaled on a stud 41. The hub of the pulley 12 is provided with a set screw 42 for securing the pulley on the sleeve.

The sleeve 17 in which the propeller shaft 13 is adjustably mounted is pivotally mounted in bearings 43 and 44 on a bracket 45, the upper end of which is provided with a U-shaped clip 46 that extends over the stern board, or outboard motor mounting 47. The lower part of the bracket 45 is provided with thumb screws 48, which are threaded in openings therein and the inner ends of the thumb screws are provided with washers 49 that contact the outer surface of the stern of the boat, which is indicated by the numeral 50.

The bracket 45 is also provided with thumb screws 80 in the upper edge for clamping the bracket to the upper edge of the stern.

The sleeve 17 is provided with set collars 51 and 52 for holding the sleeve in position in the bracket. A set screw 53 is also provided in the upper end of the sleeve for retaining the shaft in position within the sleeve.

The propeller shaft 13 and sleeve 17 are also secured in position by bearings 54 and 55 on the braces 20 and 21, respectively and the outer ends of the braces are provided with U-shaped clamps 56 and 57, similar to the clamps 32 and 33 on the ends of the braces 18 and 19.

The braces 20 and 21 are also provided with idler pulleys 58 and 59, the pulley 58 being mounted on a bearing stud 60 and the pulley 59 on a similar stud 61. The cable 70 is secured to the pulley 16 by a set screw. The shaft 13 is provided with a flat side 63 that is positioned to receive the set screw 53.

The propeller blade, as indicated by the numeral 64 is mounted through hub sections 65 and 66 on a pin 67 extended through the fork 15 and the movement of the blade is limited by outwardly extended arms 68 and 69, as shown in Figure 7.

The forward cable 29 is connected to a rear cable 70, that is trained around the pulley 16 by turn buckles 71 and 72 whereby tension in the cables may be adjusted to compensate for weather conditions and to assure successful operation of the device.

In the design shown the boat is provided with a cushion seat 73 with a back 74 and this seat is mounted upon a seat 75 extended across the stern of the boat.

With the parts arranged in this manner a comparatively slow forward and backward movement of the feet, with the feet positioned upon the pedals 27, actuates the propeller blade 64 from the full line position shown in Figure 1 to the position indicated in dotted lines and, with the propeller suspended below the bottom of the boat the pedals may be swung around through a portion of a turn to swing the propeller to the position indicated by the dotted lines 76, as shown in Figure 2, when it is desired to actuate the boat in reverse. It will also be understood that travel of the boat may be controlled by a slight shifting of the positions of the foot pedals.

With the parts arranged in this manner the rig or mounting may readily be installed upon a boat and may also be removed therefrom whereby the boat may be used with or without a fish-tail propeller mounting, as may be desired.

It will be understood that modifications may be made in the design and arrangement of the parts without departing from the spirit of the invention.

What is claimed is:

1. In a foot actuated propeller mounting for use on boats, the combination which comprises a vertically disposed shaft, a sleeve mounted on the shaft, a bearing adapted to mount the lower end of the shaft in the bottom of a boat, diagonally disposed braces having bearings on the ends thereof for supporting the upper part of the shaft and sleeve from the sides of a boat, a spider having radially disposed arms with foot pedals on the arms carried by the lower end of the sleeve, a sheave mounted on the upper end of the sleeve, a vertically disposed propeller shaft, a sleeve mounted on the propeller shaft, a bracket adapted to be positioned on the stern of a boat in which the sleeve and propeller shaft are journaled, means for clamping the bracket to the stern of a boat, diagonal braces having bearings on the ends extended from the sleeve and propeller shaft, means for clamping the ends of the braces to the sides of the boat, a pulley carried by the sleeve on the propeller shaft, cables connecting the pulleys on the propeller shaft and shaft upon which the pedals are carried, and a propeller blade carried by the lower end of the propeller shaft.

2. In a foot actuated propeller mounting for use on boats, the combination which comprises a vertically disposed shaft, a sleeve mounted on the shaft, a bearing adapted to mount the lower end of the shaft in the bottom of a boat, diagonally disposed braces having bearings on the ends thereof for supporting the upper part of the shaft and sleeve from the sides of a boat, a spider having radially disposed arms with foot pedals on the arms carried by the lower end of the sleeve, a sheave mounted on the upper end of the sleeve, a vertically disposed propeller shaft, a sleeve mounted on the propeller shaft, a bracket adapted to be positioned on the stern of a boat in which the sleeve and propeller shaft are journaled, means for clamping the bracket to the stern of the boat, diagonal braces having bearings on the ends extended from the sleeve and propeller shaft, means for clamping the ends of the braces to the sides of a boat, a pulley carried by the sleeve on the propeller shaft, cables connecting the pulleys on the propeller shaft and shaft upon which the pedals are carried, a propeller carried by the propeller shaft, and means on the propeller shaft for vertically adjusting the shaft in the said bracket.

3. In a foot actuated propeller mounting for use on boats, the combination which comprises a vertically disposed shaft, a sleeve mounted on the shaft, a bearing adapted to mount the lower end of the shaft in the bottom of a boat, diagonally disposed braces having bearings on the ends thereof for supporting the upper part of the shaft and sleeve from the sides of a boat, a spider having radially disposed arms with foot pedals on the arms carried by the lower end of the sleeve, a sheave mounted on the upper end of the sleeve, a vertically disposed propeller shaft, a sleeve mounted on the propeller shaft, a bracket adapted to be positioned on the stern of a boat in which the sleeve and propeller shaft are journaled, a set screw threaded in the sleeve for vertically adjusting the propeller shaft in the sleeve, means clamping the bracket to the stern of the boat, diagonal braces having bearings on the ends

extended from the sleeve and propeller shaft, means for clamping the ends of the braces to the sides of a boat, a pulley carried by the sleeve on the propeller shaft, cables connecting the pulleys of the propeller shaft and shaft upon which the 10
pedals are carried, a propeller blade carried by the lower end of the propeller shaft, set collars on the sleeve for vertically adjusting the sleeve and the propeller shaft vertically in the said bracket, and idler pulleys around which the cables are trained journaled on and spaced from the outer ends of the braces.

WALTER REYNOLDS.
